AUTOMATIC CLAMP

Application filed March 7, 1929. Serial No. 345,001.

This invention is an automatic clamp adapted for various uses in the several arts where it may be desired to detachably associate one part with another in clamped relation.

Speaking generally, the invention relates to that type of clamping device wherein a cam action is utilized to effect the clamping function. Devices of this broad generic type have heretofore been suggested, but they have been open to numerous objections which have rendered their practical application unsatisfactory.

My experience with devices of this general character is that the clamping action must be of a positive nature so as to obviate inadvertent displacement of the clamp part with reference to the clamping parts, and a further important requisite is that the clamp part may be readily moved into clamped relation with the clamping parts. In all of the prior devices of which I am aware, it has been necessary in order to move for example a broom handle into cooperative relation with the clamp to introduce the handle of the broom with an accompanying longitudinal movement. That is to say, the upper end of the broom must be introduced into the clamp either by lifting the movable jaw out of the way manually or by pushing the broom handle up from the bottom between the clamping jaws.

In broom closets and other places where clamps of this sort have been used, the space is frequently such as not to permit of this latter operation and it therefore becomes necessary to actually lift the movable jaw manually in order to introduce a broom.

I have referred by way of example to a broom as associated with this type of clamp, because this general type of clamp has been usually intended for such use. I wish it understood, however, that the present invention is not limited to this use, but that it is susceptible to widely varying applications. For example, it may be rigidly mounted upon a suitable support to hold articles in a detachable manner, or, on the other hand, it may be associated with some part to be supported and function in connection with a suitable stand-

ard constituting a support for the clamp and the adjunct associated therewith.

The object of the present invention is to provide a clamp operating on cam principles and free from the objections which have heretofore been universally prevalent in cam action clamps as heretofore produced.

Speaking generally, the clamp of the present invention embodies a suitable base with which is associated a fixed jaw of sufficient extent to form a relatively extensive support for the article to be clamped as opposed to the clamping action of the movable jaw. The movable jaw is in the form of a pivoted member having a curved clamping face, the curvature of which is on progressive radii. The movable jaw is mounted upon a fixed pivot and is thereby susceptible of pivotal movement, the curvature of the movable jaw being such as to have a progressive clamping action incident to progressive pivotal movement of the movable jaw.

In other words, the relation between the fixed and movable jaws is such that the clamping action becomes greater as the movement of the movable jaw proceeds. Furthermore, the particular curvature referred to is such as to well adapt the clamp to cooperate with articles of widely varying sizes, a clamp automatically compensating for variations in size through the movable jaw, partaking of positions appropriate to the size of the article to be clamped.

In practice, the movable jaw may be gravity operated or spring operated or both combined. An important practical feature of the invention resides in the provision of means for positively locking the movable jaw in clamping position; of additional or separate means for locking the article which is clamped between the jaws against inadvertent release should the jaws become separated for any reason whatever; through the provision on the fixed or movable jaw of a facing of friction material to better adapt these jaws for the performance of the functions.

A further important practical feature of this invention consists in so constructing one or both of the jaws of the clamp that an article when thrust directly against the face of

the jaws, will cause the movable jaw to retract to admit the article between the jaws, whereby the necessity of longitudinal movement of the article to introduce it between the jaws is obviated.

5 The foregoing features and others which will be apparent from the hereinafter detailed description result in a high class article of pronounced merit adapted for widely 10 varying uses and free from the objections heretofore found in prior cam action clamps.

The accompanying drawing illustrates the invention in different practical forms, but the constructions therein shown are to be understood as illustrative, only, and not as defining the limits of the invention.

Figure 1 is a front elevation of a clamp embodying the present invention and showing an article in clamped position therein.

20 Figure 2 is a section on the line 2—2 of Figure 1.

Figure 3 is a view corresponding to Figure 2, but illustrating a slightly modified form of retaining member.

25 Figure 4 is a fragmental view corresponding to Fig. 1, but illustrating a modified form of spring actuating means for the movable jaw, as well as locking means for said jaw.

The clamp of the present invention comprises a suitable base plate 1 provided at one end with a right angle flange jaw indicated at 2. The flange jaw 2 may extend uninterruptedly for the full width of the plate 1 or it may be cut away as shown at 3 to render 30 the structure lighter in weight. It is desirable, however, that the flange 2 be relatively extensive, so as to provide a long bearing surface for the article 4 to be clamped and retained in position by the clamp.

40 The flange 2 constitutes a fixed jaw of the clamp. The movable jaw designated 5 in the drawings is mounted on a pivot 6 suitably associated with the plate 1. As shown, the jaw 5 is in the form of a face plate 7 provided with a flange 8 and having a hub or boss 9 in the vicinity of the pivot. The pivot 6 extends through the boss and is anchored to the base plate 1 in a manner to allow free pivotal movement of the jaw 5 about the pivot 6. I 45 preferably employ a relatively deep flange 8 and a correspondingly deep boss or hub 9, so that the boss will provide an extensive bearing surface on the pivot and thus preclude lost motion during operation of the clamp.

50 The relatively large boss, moreover, provides a good bearing surface with the forward face of the plate 1 and thus guides the pivotal movement of the jaw 5, so that the movement is smooth and not wobbly. The 55 clamping face 10 of the jaw 5 is curved on progressive radii to form a cam surface with reference to the fixed jaw and this surface may be faced as indicated at 11 with suitable friction material such as fibre, rubber or the like. Similar friction material may be asso-

ciated with the coacting face of the jaw 2 although in practice I have found that this is not necessary. The friction material 11 may be applied merely to the face 10 or may be caused to entirely embrace the flange 8. This latter arrangement is availed of in the interest of economy of manufacture and ease of assembly.

70 It will be noted, however, that the flange 8 is notched as indicated at 12, so that the facing will not have a tendency to come off, but will be retained in position on said flange. Particular attention is called to the cut away, beveled or sloping edge 14 at the forward edge of the jaw 8. This provides a re-entrant mouth for the entrance of an article between the jaws. Thus if an article such as indicated at 4 is forced against the open side of the space between the jaws, the reentrant mouth provided by the bevel 14 will cause the edge 5 to be retracted to permit the entry of the article 4 by direct pressure of the article against the jaw. The outer edge of the jaw 2 may be similarly beveled, although in practice, I do not find this necessary.

75 The clamp as thus far defined may be used complete in which event the jaw 5 will act by gravity. I preferably, however, add additional features which will now be described.

80 In Figures 1 and 2, I have shown a catch or latch 15 associated with the jaw 2. This latch is adapted to be normally forced by a spring 16 into a position to overlie a portion of the space between the jaws so as to positively retain an article between the jaws. A 85 simplified and more economical form of latch is indicated at 16^a in Fig. 3, wherein the entire latch is in the form of a leaf spring provided with a suitable nose 17. This nose may be retracted as indicated in Fig. 3 and the movable jaw also retracted simultaneously by merely pressing the article 4 in the direction of the opening between the jaws.

90 If it is desired to make the jaw 5 spring actuated, this may be accomplished in different ways, for example, as indicated in Figures 1, 2 and 4. In Figures 1 and 2, a spring 18 is coiled around the boss or hub 9 with one end 19 of the spring hooked over the movable jaw and the other end secured by a pin 100 20 to an adjusting disk 21. This adjusting disk is freely movable about the axis of the pivot and is provided with peripheral notches 22 with which a locking pawl 23 is adapted to cooperate. The spring may be tensioned to 105 the extent desired by merely rotating the disk sufficiently to place the spring under tension and the pawl 23 will thereupon engage with a juxtaposed notch 22 to lock the parts in adjustment.

110 In the structure of Fig. 4, a somewhat different arrangement is shown. The spring 18^a is coiled about the boss and one end 19^a of the spring is secured to the movable jaw as in Fig. 1. The opposite end of the spring, 115

however, is adapted to be engaged with stationary pins 23 carried by the back plate and the tension of the spring may be controlled by simply shifting the spring into cooperation with one or the other of the pins 23 to place the spring under the desired tension.

The movable jaw may be positively locked in gripping or clamping position by such means as indicated in Fig. 4. Here the base plate 1 is shown as provided with a bracket 24 having a tapped hole through which a set screw 25 is operable. The set screw 25 is provided with a wing head 26 and after the part 4 is clamped in position, the screw 25 may be tightened to positively lock the movable jaw against movement and thus preclude any chance of removal of the article 4 until the screw 25 is retracted.

It will appear from the foregoing detailed description of the present invention that the invention provides for adjustable tension and does not depend entirely upon the gravity member but has the advantage of both gravity and adjustable tension. Furthermore, the entrance of the article into clamped position may be effected both through the bottom and by front pressure when desired. The latch at the front prevents accidental displacement and objects of any shape susceptible of being positioned between the fixed and movable jaws can be clamped in place by the structure which I have described. The friction facings may be made removable or replaceable or may be vulcanized or otherwise secured directly to the member with which they cooperate. Furthermore when an article is clamped in place, it is held by what may be termed a three-point contact pressure being applied at one point in the length of the article between two or more other points at either side of the point of application of pressure. The tendency of the article therefore to sway and thus work loose or slide with respect to the clamp parts is entirely overcome.

In practice, the flange 2 which constitutes the fixed jaw of the device may have a plane or flat face and it has been thus described. I may, however, add to the outer end of the jaw a small right angle flange 2^a extending in the direction of the movable jaw. The purpose of this flange is to facilitate the gripping of articles of such size as will not entirely enter between the jaws but will rather project outside of the jaws. The flange 2^a provides a better contact for such articles and assures the tighter gripping of the same. The flange 2^a is desirable even with small articles for in many uses it obviates the necessity or desirability of employing the latches 15 or 17.

Having thus fully described the invention, what I claim as new and desire to secure by Letters Patent is:

1. An automatic clamp embodying a base provided thereon with a forwardly projecting

flange constituting a fixed jaw, a pivot extending forwardly from a point in the base remote from the fixed jaw, an arm having a rearwardly extending hub embracing the pivot and spacing the arm from the base, a rearwardly extending flange, constituting a movable jaw, formed on the arm and having a curved cam shaped clamping face positioned in opposed relation to the fixed jaw to provide between the jaws a recess to receive an article to be clamped, and a spring coiled about said hub between the base and the arm with one end of the spring secured to the arm and the other end of the spring anchored, with respect to the base, said spring being tensioned to impel the movable jaw into clamping relation with the fixed jaw.

2. An automatic clamp embodying a suitable base provided thereon with a fixed jaw, a movable jaw mounted for pivotal movement on the base and having a curved cam shaped clamping face positioned in opposed relation to the fixed jaw to provide between the clamping faces of the fixed and movable jaws a recess to receive an article to be clamped, at least one of said jaws being beveled at the open side of said recess to provide a reentrant mouth through which articles may be forced into the space between the jaws, said bevel being shaped to cause retraction of the movable jaw when an article is forced into the reentrant mouth to permit entrance of said article into the mouth, a spring coiled about the pivot of the movable jaw with one end of the spring secured to said jaw, and means for anchoring the opposite end of the spring with the spring under varying degrees of tension.

3. An automatic clamp embodying a suitable base provided thereon with a fixed jaw, a movable jaw mounted for pivotal movement on the base and having a curved cam shaped clamping face positioned in opposed relation to the fixed jaw to provide between the clamping faces of the fixed and movable jaws a recess to receive an article to be clamped, at least one of said jaws being beveled at the open side of said recess to provide a reentrant mouth through which articles may be forced into the space between the jaws, said bevel being shaped to cause retraction of the movable jaw when an article is forced into the reentrant mouth to permit entrance of said article into the mouth, and a latch normally extending at least partially across the reentrant mouth to preclude inadvertent displacement of an article positioned in said mouth, said latch being retractable when it is desired to remove the article.

4. An automatic clamp embodying a suitable base provided thereon with a fixed jaw, a movable jaw mounted for pivotal movement on the base and having a curved cam shaped clamping face positioned in opposed relation to the fixed jaw to provide between the clamp-

ing faces of the fixed and movable jaws a recess to receive an article to be clamped, at least one of said jaws being beveled at the open side of said recess to provide a reentrant mouth through which articles may be forced into the space between the jaws, said bevel to cause retraction of the movable jaw when an article is forced into the reentrant mouth to permit entrance of said article into the mouth, a spring coiled about the pivot of the movable jaw with one end of the spring secured to said jaw, means for anchoring the opposite end of the spring with the spring under varying degrees of tension, and a latch normally extending across the reentrant mouth to preclude inadvertent release of the article through said mouth.

5. An automatic clamp embodying a suitable base provided thereon with a fixed jaw, a movable jaw mounted for pivotal movement on the base on a fixed axis and having a curved cam shaped clamping face positioned in opposed relation to the fixed jaw to provide between the clamping faces of the fixed and movable jaws a recess to receive an article to be clamped, at least one of said jaws being beveled at the open side of said recess to provide a reentrant mouth through which articles may be forced into the space between the jaws, said bevel being shaped to cause retraction of the movable jaw when an article is forced into the reentrant mouth to permit entrance of said article into the mouth, and means for positively locking the movable jaw against rotative movement on said fixed axis and in clamped position with respect to said article.

In testimony whereof I have signed the foregoing specification.
